[57] CLAIM

The ornamental design for computerized measuring machine for weight, height and temperature, substantially as shown and described.

DESCRIPTION

FIG. 1 is a front elevational view of a computerized measuring machine for weight, height and temperature showing my new design;

FIG. 2 is a rear elevational view thereof;

FIG. 3 is a right side elevational view thereof;

FIG. 4 is a left side elevational view thereof;

FIG. 5 is a bottom plan view thereof;

FIG. 6 is a top plan view thereof;

FIG. 7 is a bottom plan view of the head portion of the machine, the lower portions being omitted for ease of illustration;

FIG. 8 is a left front perspective view thereof.

FIG. 6

FIG. 3

FIG. 5

FIG. 4

FIG. 7

FIG. 8
